INVENTOR

Carl H. Drummond,
By B. B. Macklin,
Attest.

UNITED STATES PATENT OFFICE.

CARL H. DRUMM, OF EAST CLEVELAND, OHIO.

SHINGLE.

Application filed October 4, 1923. Serial No. 666,434.

To all whom it may concern:

Be it known that I, CARL H. DRUMM, a citizen of the United States, residing at East Cleveland, in the county of Cuyahoga and State of Ohio, have invented a certain new and useful Improvement in Shingles, of which the following is a full, clear, and exact description, reference being had to the accompanying drawings.

10 This invention relates particularly to improvements in prepared roofing, wherein the overlapping courses are arranged to simulate the appearance of a shingled roof, having spaces between adjacent shingles.

15 Usually prepared shingles, made for the specific purpose of simulating the appearance of a shingled roof, have portions thereof recessed, wherefore the shingles are self spacing when laid side by side in a row 20 to form a course. The recessed portions extend along the side of the shingle in accordance with the amount thereof adapted to be exposed to the weather. One of the 25 principal objections to self-spacing shingles is that they cannot be inverted without destroying the continuity of a course. Accordingly if a shingle is defective on the portion adapted to be exposed to the weather, then it has been necessary to discard the entire shingle.

One of the objects of my invention therefore, is the provision of a self-spacing shingle which may be inverted end for end, thus enabling the shingle to be satisfactorily 35 used in the event of a defect occurring in the portion which is adapted to be exposed to the weather.

In addition, my invention contemplates the provision of a shingle which may be 40 cut from prepared roofing with a minimum of waste, and which is well adapted for permitting the different sizes to be made in accordance with the amount arranged to be exposed to the weather.

45 Other objects of my invention will be apparent, to those skilled in the art to which my invention relates, from the accompanying drawing taken in connection with the following description.

50 In the drawings Fig. 1 is a plan view of a plurality of shingles made in accordance with my invention and showing them arranged side by side and spaced in aligned relationship; Fig. 2 is a plan view showing 55 two shingles placed side by side; Fig. 3

is a similar plan view showing one of the shingles inverted.

My invention embodies a shingle construction which permits any shingle to be inverted with relation to an adjacent shingle 60 while being laid. Accordingly, in the drawings I have illustrated a shingle which may be stamped out of suitable material, such as asphalt, or composition by a suitable die. For purposes of illustration, a shingle indicated at 10 has a projection 11 and a recess 12 along one side with a corresponding projection 11^a and recess 12^a on the opposite side. The step like sides divide the shingle into an upper portion indicated 65 at A, a lower portion indicated at B, and an intermediate portion C.

The relation between each projection and recess is such that the difference between the width of the recess and that of the projection is equal to the space between the the exposed portions of adjacent shingles. Accordingly to permit inversion of a shingle, the length of the projection is substantially equal to the length of the corresponding recess, wherefore the area of the top portion is equal to the area of the bottom portion. Moreover the median lines 80 through the top and bottom are offset an equal distance in opposite directions from 85 the median line of the intermediate portion.

An advantage of a shingle made in accordance with my invention may be illustrated by referring to Fig. 2 wherein two shingles designated 10 and 20 are laid side by side with the sides of the intermediate portions in abutting engagement. Here it will be seen that the space between the top portion is equal to the space between the bottom portion. Referring now to Fig. 3, shingle 20 is inverted with relation to shingle 10 while the continuity of arrangement is not affected.

Referring now to Fig. 1, I have shown 100 a plurality of shingles arranged side by side and overlapping in the usual way to form a covering. In laying the shingles the workmen need only bring a side of the intermediate portion of a shingle into abutting engagement with a side of the intermediate portion on the adjacent shingle. This automatically effects an alignment and insures a proper spacing between the exposed portions of adjacent shingles. 105 110

In view of the foregoing description, it will be readily understood that my invention permits the inversion of an interlocking shingle without eliminating the space 5 between the exposed portions of adjacent shingles. Moreover this inversion may be accomplished without necessitating the cutting of any shingle in order to obtain a proper joint. A further advantage of a 10 shingle made in accordance with my invention is the fact that the shingle may be cut from a roll with a minimum of waste.

I claim:

1. A shingle having interlocking sides 15 comprising a projection and a recess on each of a pair of opposite sides, the position of the projections and recesses being such that the projections are inverted relatively to each other and the recesses are inverted relatively to each other, whereby a correlated similar shingle may be disposed in alignment therewith either in normal or in inverted position without varying the spacing distance between adjacent shingles.

25 2. A shingle having projections and recesses on each of a pair of opposite sides thereof, the recesses having a width greater than that of the projections, the projections and recesses on the opposite sides being so 30 positioned that the projections are inverted relatively to each other and that the recesses are inverted relatively to each other, whereby one shingle may be disposed in lateral alignment with another, either in normal or 35 in inverted position without affecting the spacing between the adjacent shingles.

3. A shingle having a projection and a recess along each of a pair of opposite sides thereof, the projections being spaced on 40 diagonally opposite ends of the shingle and the recesses being spaced on other diagonally opposite ends of the shingle, whereby the projections are inverted relatively to each other and the recesses are inverted relatively 45 to each other, each of said projections being narrower than the associated recesses whereby one shingle may be disposed in lateral alignment with another shingle either in normal or inverted position without affecting 50 the continuity of the exposed edges, and without varying the spacing distance between adjacent shingles.

4. A shingle having a projection and a recess along each of a pair of opposite sides

thereof, the projections being inverted relatively to each other and the recesses being inverted relatively to each other, the projections and recesses being respectively similarly formed and having different widths, whereby one shingle may be inverted 55 with relation to an adjacent shingle without varying the spacing distance therebetween.

5. A shingle having projections and recesses on each of a pair of opposite sides thereof, the projections having equal length, 60 and being of less width than the recesses by an amount equal to the spacing distance between the exposed portions of adjacent shingles.

6. A shingle having a projection and a recess on each of a pair of opposed sides, the projection and recess on one side being inverted with relation to the projection and recess on the opposite side, and each projection having less width than the corresponding recess.

7. A shingle having a projection and a recess along one side thereof and having a corresponding projection and recess along the opposite side thereof, the projections and recesses being so positioned that the projections are inverted relatively to each other and the recesses are inverted relatively to each other, the projections and recesses having different widths, whereby the shingle 85 may be laid either in normal or in inverted position without affecting the normal spacing distance of the shingle with relation to an adjacent shingle.

8. A shingle having a projection and a recess along each of a pair of opposed sides thereof, the projections being inverted relatively to each other and the recesses being inverted relatively to each other, the projections being equal in width and the recesses being equal in width but the projections being narrower than the recesses, whereby one shingle may be laid in lateral alignment with other shingles either in normal or inverted position, without affecting 100 the spacing distance between the exposed portions of the shingle and without affecting the continuity of the exposed edges of adjacent shingles.

In testimony whereof, I hereunto affix my 105 signature.

CARL H. DRUMM.
